UNITED STATES PATENT OFFICE

171,655

TOY ANIMAL

Mary Louise Love, Monrovia, Calif.

Application June 26, 1953, Serial No. 25,684

Term of patent 14 years

(Cl. D34—2)

To all whom it may concern:

Be it known that I, Mary Louise Love, a citizen of the United States, residing at Monrovia, in the county of Los Angeles, State of California, have invented a new, original, and ornamental Design for a Toy Animal, of which the following is a specification, reference being had to the accompanying drawing, forming a part thereof.

Fig. 1 is a side elevational view of a toy animal showing my new design.

Fig. 2 is a front elevational view.

Fig. 3 is a rear elevational view.

I claim:

The ornamental design for a toy animal, as shown.

MARY LOUISE LOVE.
